FUEL INJECTOR

Harry F. Haines, Canton, Ohio, assignor to The Timken Roller Bearing Company, Canton, Ohio, a corporation of Ohio

Application July 5, 1941, Serial No. 401,233

3 Claims. (Cl. 299—107.6)

This invention relates to fuel injectors for compression ignition engines, and more particularly to fuel injectors of the type having a spring-loaded valve that is opened hydraulically by the fuel pressure. The invention has for its principal object to improve the means for limiting the opening movement or lift of the valve and the means for transmitting the end thrust between the valve and valve spring. Other objects are simplicity, cheapness and durability of construction and compactness of design. The invention consists in the fuel injector and in the construction, combinations and arrangements of parts hereinafter described and claimed.

In the accompanying drawing, which forms part of this specification and wherein like symbols refer to like parts wherever they occur,

Fig. 1 is a central longitudinal section through a fuel injector embodying my invention; and

Fig. 2 is an enlarged central longitudinal section through the injector in the region of the end thrust transmitting thimble.

In the accompanying drawing, my invention is shown embodied in a fuel injector for an internal combustion engine of the Diesel type. The injector comprises a nozzle holder A having a fuel inlet or supply passageway 1 that leads inwardly through one side of said holder and thence downwardly through the lower end thereof. The cylindrical nozzle or jet element B of the injector is rigidly secured to the lower end of the holder A by means of a sleeve nut C that is threaded on said end and has an internal annular shoulder 2 adapted to bear against the external annular shoulder 3 on said nozzle and thus rigidly clamp the same in endwise abutting relation to the holder. The nozzle B has an axial bore 4 extending therethrough that is enlarged adjacent to its lower end to form a chamber 5; and communication is established between the fuel inlet or supply passageway 1 and said chamber through an annular groove 6 in the upper end of said nozzle and one or more passageways 7 leading from said groove to said chamber.

Reciprocable in the bore 4 of the nozzle B is a cylindrical plunger 8 which terminates at its lower end in a pin 9 that cooperates with the lower end of said bore to form an annular discharge orifice 10. The plunger 8 is provided just above the pin 9 with an annular valve portion or element 11 adapted to cooperate with an annular valve seat 12 in the chamber 5 and thus prevent flow of fuel through the annular discharge orifice 10. The plunger also has a conical portion 13 located in the chamber 5, whereby

the plunger is adapted to be forced upwardly in the nozzle to lift the valve 11 off its seat by the hydraulic pressure of the fuel on said conical portion.

5 The plunger 8 has its upper end reduced to form a stem portion 14 upon which is supported an end thrust member or thimble 15 located in the lower end portion of a bore 16 that extends through the holder A from top to bottom thereof in axial alignment with the axial bore of the nozzle B. The thimble 15 seats on the upper end of the stem 14 of the plunger 8 with its lower end disposed clear of the annular shoulder 17 formed by said stem and enlarged to form an annular stop shoulder or collar 18; and the bore 16 in the holder A is enlarged or counterbored, as at 19, where it opens through the nozzle receiving end of said holder, to provide an annular stop or abutment shoulder for the stop shoulder 18 of said thimble. The plunger 8 is snugly guided in the axial bore 4 of the nozzle B; and an annular clearance space is preferably provided between the thimble 15 and the bore 16 of the nozzle holder A. The bore 16 of the holder is 15 enlarged near the upper end of the thimble 15 to receive a coil compression valve closing spring 20; and said thimble is provided near the upper end thereof with a slip or snap ring 21 adapted, when the nozzle B is detached from said holder, to abut against the annular shoulder 22 formed by such enlargement and thus retain said thimble in said holder. The thrust member or thimble 15 has its upper end member reduced to form an annular shoulder or seat 23 for the lower end 20 of the valve closing spring 20. The upper end of the spring receiving bore 16 is closed by a threaded plug 24, which forms a seat for the upper end of the valve spring 20; and this plug has an axial extending pin 25 depending therefrom which extends downwardly through the spring and serves as a guide therefor. Shims 26 are disposed between the upper end of the spring 20 and the lower end of the plug 24, whereby the pressure of said spring may be regulated or adjusted. The holder A has a passageway 27 therein leading from the spring receiving bore 16, the purpose of this passageway being to return to the service or supply tank (not shown) for the injector any fuel that may leak past the plunger 8 into said bore.

45 By the arrangement described, the pressure of the valve closing spring 20 is transmitted to the plunger 8 through the relatively short and rigid spring thrust member or thimble 15 seated on top of the stem 14 at the upper end of said

plunger. The nozzle is opened by the pressure of the fuel on the conical portion 13 of the plunger, which pressure forces the plunger upwardly against the pressure of the spring 20, thereby lifting the valve element 11 of said plunger off its seat and permitting the fuel to escape through the annular discharge orifice 10. The lift, or opening movement of the valve is fixed or limited by the annular abutment formed by the counterbored or enlarged outer end portion 19 of the bore 16 in the holder A, the stop shoulder 18 near the lower end of the spring thrust thimble 15 abutting against this abutment in the open position of the valve.

What I claim is:

1. A fuel injector comprising a holder having a bore opening through one end thereof, a nozzle secured to said end of said holder and having a bore therethrough in register with the holder bore, the nozzle bore terminating at its outer end in a discharge orifice and having a valve seat therein inwardly of the latter, communicating fuel supply passageways in said holder and nozzle opening into said nozzle bore inwardly of the valve seat therein, a plunger reciprocable in said nozzle bore and having a valve element cooperating with the valve seat therein, a thimble axially slidible in the nozzle opposing end of the body bore, the inner end of said plunger extending into said thimble, and a spring in said holder bore for holding said thimble in abutting relation to said plunger and the valve element of said plunger on said valve seat, said body bore having an outwardly facing shoulder therein and said thimble having an external shoulder thereon adapted to abut against said first mentioned shoulder to thereby limit the inward movement of said plunger and the lift of the valve element of the latter.

2. A fuel injector comprising a holder having a bore opening through one end thereof, a nozzle secured to said end of said holder and having a bore therethrough in register with the holder bore, the nozzle bore terminating at its outer end in a discharge orifice and having a valve seat therein inwardly of the latter, communicating fuel supply passageways in said holder and nozzle opening into said nozzle bore inwardly of the valve seat therein, a plunger reciprocable in said nozzle bore and having a valve element cooperating with the valve seat therein, a thimble axially slidible in the nozzle opposing end of the body bore, the inner end of said plunger extending into said thimble, and a spring in said holder bore for holding said thimble in abutting relation to said plunger and the valve element of said plunger on said valve seat, said body bore having an outwardly facing shoulder therein and said thimble having an external shoulder thereon adapted to abut against said first mentioned shoulder to thereby limit the inward movement of said plunger and the lift of the valve element of the latter.

3. A fuel injector comprising a holder having a bore opening through one end thereof, a nozzle secured to said end of said holder and having a bore therethrough in register with the holder bore, the nozzle bore terminating at its outer end in a discharge orifice and having a valve seat therein inwardly of the latter, communicating fuel supply passageways in said holder and nozzle opening into said nozzle bore inwardly of the valve seat therein, a plunger reciprocable in said nozzle bore and having a valve element cooperating with the valve seat therein, a thimble axially slidible in the nozzle opposing end of the body bore, the inner end of said plunger extending into said thimble, and a spring in said holder bore for holding said thimble in abutting relation to said plunger and the valve element of said plunger on said valve seat, said body bore having an outwardly facing shoulder therein and said thimble having an external shoulder thereon adapted to abut against said first mentioned shoulder to thereby limit the inward movement of said plunger and the lift of the valve element of the latter.

4. A fuel injector comprising a holder having a bore opening through one end thereof, a nozzle secured to said end of said holder and having a bore therethrough in register with the holder bore, the nozzle bore terminating at its outer end in a discharge orifice and having a valve seat therein inwardly of the latter, communicating fuel supply passageways in said holder and nozzle opening into said nozzle bore inwardly of the valve seat therein, a plunger reciprocable in said nozzle bore and having a valve element cooperating with the valve seat therein, a thimble axially slidible in the nozzle opposing end of the body bore, the inner end of said plunger extending into said thimble, and a spring in said holder bore for holding said thimble in abutting relation to said plunger and the valve element of said plunger on said valve seat, said body bore having an outwardly facing shoulder therein and said thimble having an external shoulder thereon adapted to abut against said first mentioned shoulder to thereby limit the inward movement of said plunger and the lift of the valve element thereof.

5. A fuel injector comprising a holder having a bore opening through one end thereof, a nozzle secured to said end of said holder and having a bore therethrough in register with the holder bore, the nozzle bore terminating at its outer end in a discharge orifice and having a valve seat therein inwardly of the latter, communicating fuel supply passageways in said holder and nozzle opening into said nozzle bore inwardly of the valve seat therein, a plunger reciprocable in said nozzle bore and having a valve element cooperating with the valve seat therein, a thimble axially slidible in the nozzle opposing end of the body bore, the inner end of said plunger extending into said thimble, and a spring in said holder bore for holding said thimble in abutting relation to said plunger and the valve element of said plunger on said valve seat, the nozzle opposing end of said body bore being counterbored to form an outwardly facing annular shoulder therein, and said thimble having a collar adapted to abut against said outwardly facing shoulder of said body bore to thereby limit the inward movement of said plunger and the lift of the valve element thereof.

6. A fuel injector comprising a holder having a bore opening through one end thereof, a nozzle secured to said end of said holder and having a bore therethrough in register with the holder bore, the nozzle bore terminating at its outer end in a discharge orifice and having a valve seat therein inwardly of the latter, communicating fuel supply passageways in said holder and nozzle opening into said nozzle bore inwardly of the valve seat therein, a plunger reciprocable in said nozzle bore and having a valve element cooperating with the valve seat therein, a thimble axially slidible in the nozzle opposing end of the body bore, the inner end of said plunger extending into said thimble, and a spring in said holder bore for holding said thimble in abutting relation to said plunger and the valve element of said plunger on said valve seat, the nozzle opposing end of said body bore being counterbored to accommodate said annular rib and to provide in said body bore an annular abutment for said annular rib to thereby limit the inward movement of said plunger and the lift of the valve element thereof.
